(57) **CLAIM**

The ornamental design for an air conditioner, as shown and described.

DESCRIPTION

FIG. 1 is a front perspective view of an air conditioner showing my new design;

FIG. 2 is a front elevation view thereof;

FIG. 3 is a rear elevation view thereof;

FIG. 4 is a right side elevation view thereof, the left side view being a mirror image;

FIG. 5 is a top plan view thereof;

FIG. 6 is a bottom plan view thereof;

FIG. 7 is an enlarged cross sectional view taken along line 7-7 of FIG. 2 thereof;

FIG. 8 is an enlarged detail view of the selected portion of FIG. 1 thereof; and,

FIG. 9 is a front perspective view of an air conditioner shown in FIG. 1 thereof, showing the louver in an open position.

The dash-dot-dash broken lines shown in FIG. 1 and FIG. 8 indicate cutoff boundaries for enlarged detailed portion views and form no part of the claimed design.

The dashed broken lines depict portions of the air conditioner that form no part of the claimed design.

The drawings include surface shading which illustrates contour and not surface ornamentation.
